Res. 399

Apollos Richmond Providence P. S.
Letters Patent ^{no} 399. dated July 15th 1851.
(assigned to A. C. Barstow & Co.)

The schedule referred to in these letters patent and making part of the same
to all persons to whom these presents shall come. Be it known that Apol
los Richmond of Providence in the County of Providence and State of Rhode
Island have produced a new and original Design for the top and
front plates of a parlor stove, and I do hereby declare that the said new
design is fully described and represented in the following specification
and drawings to which reference is hereinafter made.

My new design is represented in the accompanying plates of drawings. In
plate 1. fig 1. is an elevation of the front plate. In plate 2. fig 2.
is a section of the front plate taken in the plane of the line
A B. fig 1. - In pl. 3. Fig 3. is a plan of the top plate and Fig 4
a section of the same taken in the plane of the line C D.
The front plate is ornamented as follows - across the top are placed

the Norman arches a.a.a. &c. Under there is another set of arches b.b. the sets of arches being separated by the mouldings c.d.e. On the sides of this plate are the mouldings ^{or pilasters} f.f. resting on the mouldings g.g. &c. in the bottom of the plate. Near to these pilasters are the sunken arched panels h.h. formed by the mouldings i.i.i. &c. These panels have in them the ornamental figures k.k. in the centre and the spear heads l.l. at each end. The fire chamber door m. panel n. and ash pit door o. which occupy the central portion of the plate have around each of them the heads p.p. and the mouldings q.q. &c.

The door m. and the panel n. have on them the arched mouldings r.r. the architraves s.s. and the mouldings t.t. with spear heads on them. Inside of the arched mouldings r.r. on the panel n. are the ornamental figures u.u.u. The top plate which is of the shape shown in plate 3. has around its edge the similar raised mouldings v.v. &c. The space between the upper of these mouldings v.v. and the moulding w.w. is ornamented by the curved figures formed by the mouldings x.x. spear heads y.y. &c. On the top panel are openings covered by the semi circular plates z.z. with the beads f.f. &c.

Having thus described my new design I shall state my claim as follows. What I claim as my production and deserve to have secured to me by letters patent is the design consisting of the ornamental arches panels and mouldings herein above described and represented in the drawings respectively for the front and top plates of a parlor stone
